PREFABRICATED BUILDING STRUCTURE

Harold S. Shannon, Detroit, Mich., assignor to
 National Steel Corporation, a corporation of
 Delaware

Application November 16, 1945, Serial No. 629,084

1 Claim. (Cl. 189—1)

1 This invention relates generally to building construction and more particularly to buildings having a modular plan of construction.

One of the objects of the present invention is to provide new and improved building structure of the character in which the dimensions of the building elements have a definite, predetermined relationship with respect to a modular plan of construction.

Another object of the invention is to provide building structure including a plurality of novel studs of a structural character such that they may be used singly or be combined in various ways to satisfy all of the studding requirements of a building.

Another object of the invention is to provide for flexibility of arrangement and construction of paneled partitions in a building constructed on a modular plan.

Another object of the invention is to provide a new and novel building stud, constructed to readily cooperate in joining interior and exterior wall panels and also in joining interior walls.

Other objects of the invention will become apparent from the following detailed description taken in connection with the accompanying eight sheets of drawings in which:

Figure 1 is a floor plan view of a building showing exterior and interior walls arranged in accordance with a modular plan of construction and embodying features of the invention;

Figure 2 is a horizontal cross sectional view of two combinable, similar building studs, shown separated, used in the building of Figure 1;

Figure 3 is a cross sectional view of two combinable, dissimilar building studs for a corner of an interior wall of the building of Figure 1;

Figure 4 is a fragmentary horizontal sectional view of the building of Figure 1 showing the studding and paneling of exterior and interior walls with respect to the modular plan;

Figure 5 is a cross sectional view of the pair of similar studs of Figure 2, taken along the line 5—5 of Figure 13, showing the two similar studs in their relative positions when forming part of an interior wall;

Figure 6 is a plan view of a type of stud used singly at a room corner;

Figure 7 is a plan view of another type of corner stud;

Figure 8 is a fragmentary cross sectional view of interior wall paneling and a pair of combined studs of a different form;

Figure 9 is a fragmentary sectional view, taken along the line 9—9 of Figure 8, showing how the

2 combined stud of Figure 8 is secured at top and bottom thereof;

Figure 10 is a fragmentary elevational view partly broken away and in section of an interior wall panel structure including a two-part stud of the type shown in Figures 2 and 5;

Figure 11 is a vertical sectional view of the interior wall, taken along the line and in the direction of the arrows 11—11 of Figure 10;

Figure 12 is a vertical sectional view of the panel structure for an exterior wall;

Figure 13 is a view similar to Figure 10 showing one of the studs in side elevation with the panels removed;

Figure 14 is a vertical sectional view of an interior wall and stud, taken along the line 14—14 of Figure 13;

Figure 15 is a vertical sectional view of a stud and supporting structure for an exterior wall;

Figure 16 is an interior perspective view of a corner structure shown partly broken away and in section;

Figure 17 is a view similar to Figure 4 showing a modified form of building structure;

Figures 18 and 19 are enlarged fragmentary sectional views of detail structure of the building of Figure 17;

Figure 20 is a vertical sectional view of an interior wall of the building of Figure 17;

Figures 21, 22 and 23 are fragmentary perspective views showing details of panel attaching means, and

Figure 24 is a plan view showing one of the panel fasteners detached from its cooperating fastening elements on the panels.

Referring to the drawings by characters of reference and first to Figure 1, the modular plan is illustrated by the dividing of a given area, depending upon the size of the building, into a number of equal squares or whole parts thereof by horizontal and perpendicular lines. These squares are hereinafter referred to as modules and the lines, designated ML, as module lines. In the present instance, the outer peripheral modular lines are coincident with the inner wall surfaces of exterior walls 11 of the building. The inner wall surfaces of exterior walls 11 are covered by panels and connecting studs, which are hereinafter described in detail and the area therewithin is divided into the desired number and size rooms by interior walls or partitions such as those designated generally by the numerals 12, 13 and 14, see Figure 4. As shown in the drawings, the interior walls or partitions 12, 13 and 14 are located so that vertical medial

50 55

planes thereof are coincident with selected module lines. With particular reference to Figures 1 to 15 inclusive, the building includes a floor 15 and a ceiling 16, the ceiling 16 being a predetermined height from the floor and being supported by the exterior walls 11 of the building. The inner surfaces 10 of the exterior walls 11 are covered by a plurality of panels 17 each of which preferably comprises an external sheet of a suitable heat and sound insulating material 18 which may be cemented or otherwise suitably secured to the outer surface of a finish panel 19 and the interior walls are formed by panels 17' which may be the same in construction and size as the exterior wall panels 17.

All of the studs along exterior walls 11 are secured at top and bottom to metallic securing strips 20 which in turn are respectively secured to the floor 15 and to the ceiling 16, see Figures 12 and 15. These strips 20 are provided with longitudinally extending outturned flanges 21 having flange portions 22 thereof bent at substantially right angles to provide good seating surfaces for engaging the inner surfaces of the exterior walls 11, coincident with the outer lines of the modular plan. Inturned upper and lower flanges 23 respectively of the upper and lower strips 20 seat against the floor or ceiling as the case may be and may be apertured to receive wood screws for securing the strips 20 thereto.

In order to reduce the cost of stud fabrication and also to facilitate erection of the building structure, I provide three different types of studs or panel connectors designated generally by the numerals 24, 25 and 26, see Figure 4. These studs are so formed and constructed that they may be employed singly in certain locations and combined in various ways for use in other locations to provide all the necessary studding for a building without reworking any of the parts on the job or at the site of erection of the building. Referring first to the stud 24, this stud may be used singly, for example, at the corner of a room where adjacent exterior walls 11 form a substantially 90° interior corner as seen at the lower left in Figure 4. The stud 24 is preferably formed of sheet steel for strength and durability and is an elongated strip-like member to extend vertically between the floor 15 and the ceiling 16 of the building. As seen in cross section, the stud 24 has a stepped wall including a centrally disposed angle portion 27, the sides of which are substantially normal to each other to form a corner and provide abutment surfaces 27' for side edges of adjacent panels 17. Flanges 28, bent so that they are normal to adjacent abutment surfaces 27' of the angle portion 27, provide seating surfaces respectively for side portions of the adjacent corner forming panels 17. The flanges 28 are spaced from the respective parallel abutment surfaces 27' so that the depths of the abutment surfaces or shoulders 27' are equal to the widths of the panels 17, thus providing a stud presenting two relatively right angled tongues to permit the panel edges to meet in a neat appearing corner construction. Further, the flanges 28 are each reversely bent in spaced relation thereto, as shown, to provide seating flanges 29 for seating against the exterior wall inner surfaces 10, coincident with the intersecting module lines. As shown more clearly in Figure 16, the stud flanges 28 and their reversely bent portions 29 terminate below and in spaced relation to the upper stud securing strips 20, but the central angle portion 27 projects thereabove to receive self-threading

screws 30 which screw into the securing strips 20 to secure the stud thereto. Similarly, the lower end of the stud (not shown) may have an extended angle portion for securing the stud at its lower end to the floor strip 20. The stud flanges 28 and the panels 17 are provided with aligning apertures to receive self-threading screws 31' to secure the panels to the studs.

Referring now to the stud 25, this stud is used singly at a corner of the building where two adjacent exterior walls come together to form a substantially 270° interior corner, as seen at the lower right of Figure 4. The corner stud 25 includes an elongated metallic stud member or backing strip 25' of angle form having substantially relatively perpendicular sides 31 extending between the floor 15 and the ceiling 16. Outer side edge portions 32 of the stud sides 31 are reversely bent back in spaced relation respectively to the outer or adjacent surfaces of the sides 31 to seat against inner surfaces of the exterior walls 11 and thus coincide with the outer module lines. Secured to the inner surfaces of the stud member sides 31 at top and bottom thereof is an angle-like metallic strap 33, see Figure 7, providing offset, upper and lower extended end portions for the stud member 25'. Between the inner ends of the extension member 33 extends a strip 34 of board-like sound and heat insulating material and the straps 33 and insulation board 34 are covered by a wooden finish panel strip 35. The insulation panel 34, and the finish board 35 are, like the metallic stud member 25, of angular cross section fitting complementary to each other with the terminal edges thereof spaced from the side edges of the metallic stud member to provide seating surfaces for side border portions of adjacent panels 17. The straps 33 have inturned flanges 36 arranged with the edges thereof abutting the stud sides 31 where the parts may be welded together. The finish panel 35 and insulation board 34 are made substantially the same width and are arranged to provide flush edges for opposed relation with side edges of adjacent panels 17. The sum of the thickness of the finish panel 35 and the width of the strap flanges 36 is equal to the thickness of the adjacent wall panel 17 so that a continuous unbroken inner wall surface is provided. Screws, such as those shown and designated 38, Figure 12, may be provided to secure the adjacent panels 17 to the exposed side edge portions of the metallic stud member 25, or, the parts may be secured together by any other suitable means.

The third type of stud, designated generally by the numeral 26, comprises an elongated metallic stud member 40, upper and lower metallic extensions or straps 41, a sound and heat insulating strip 42 and a finish stud panel strip 43. The length of the metallic stud member 40 is made such that when erected, its upper and lower ends will be spaced respectively from the upper and lower securing strips 20, but the metallic straps 41 and the finish panel strip 43 project beyond the ends of member 40 to overlie the upper and lower securing strips 20 where they are apertured to receive screws 43', see Figure 15, for securing the stud to the strips 20. Longitudinal edge portions of the stud member 40 are inturned, as at 44, in spaced relation thereto to provide seating surfaces for seating against the inner surface of exterior wall 11 coincident with the outer module line. As shown in Figures 4 and 5, the stud member 40 is wider than the straps 41, insulation board 42 and strip finish panel 43, the edges of

which terminate flush with each other inwardly of the side edges of the stud member 40 to leave seating surfaces for side edge portions of adjacent panels 17. The straps 41 are provided with inturned reinforcing side flanges which abut the inner surface of stud members 40 where the parts may be welded or otherwise suitably secured together. This stud member 26 provides what may be termed a double joint since the insulation strip 42, straps 41 and finish panel 43 space adjacent edges of panels 17 apart forming two joints at the stud. In accordance with my modular plan, the widths of the strip 42, straps 41 and finish strip 43 are equal to each other and in this instance, are equal to twice the distance from the inner surface of the exterior wall 11 to the inner surface of the panels 17 to provide for uniformity of partition panel widths and flexibility of locating and relocating interior walls or partitions. All of the studs of the type of studs 25 and 26 or those studs which are constructed of several parts comprising a metallic backing strip, upper and lower metallic straps, filler insulation and finish board, are constructed to provide for vertically adjusting the position of the metallic backing strip relative to the finish strip so that the screw holes in the backing strip can be properly aligned with the screw holes in the finish panels 17 or in the finish panel 17', as the case may be. To this end, the straps or offset metallic extensions 41 of Figures 14 and 15, for example, are provided with vertically elongated clearance apertures to receive the screws 43' thus permitting vertical adjustment of the backing member 40, straps 41 and insulation 42 as a unitary structure, it being understood that the finish panel 43 is secured to the other stud parts only by the clamping actions of the screws 43'. Thus, the backing member 40 can be vertically adjusted relative to the finish strip until the screw holes in the backing member properly align with corresponding screw holes in the panels after which screws 38 are tightened and screws 43' are tightened to secure the stud parts together and to the top and bottom securing strips 20.

Where the interior wall or partition 12 formed by panels 17' joins to the exterior wall paneling 17, two of the stepped wall studs 24 are combined as a double stud, designated generally by the numeral 45, of a character presenting seating surfaces and abutments for the paneling 17' of the interior walls, as well as for adjacent panels 17 of the exterior wall 11. These two studs 24 are arranged with the outer faces of a pair of corresponding reversely bent flanges 29 in abutting relation, the other corresponding reversely bent flanges 29 being spaced apart and seating against the inner surface of the exterior wall 11, coincident with the outer module line. In accordance with my modular plan, with reference to the double stud 45, the distance from either of the abutment shoulders or opposed surfaces 27' to the parallel module line in the vertical medial plane of partition 12 is equal to the distance from the inner surface of exterior wall 11 to the inner surface of the panels 17. In other words, the distance between the abutment surfaces 27' is equal to the width of the partition 12, providing for the use of panels of equal widths and thickness for both the exterior wall 11 and the partition 12 provided that the so-called double joint paneling system is used throughout the entire length of the partition.

Another form of studding, designated generally by the numeral 47, comprises two of the

studs 26 which together may be used for securing thereto intermediate panels of the interior wall or partition 12 or panels other than the corner panels of a room. The studs 26 are arranged such that corresponding inturned flanges 44 thereof are in abutting relation with each other, the flange surfaces abutting in the medial plane of the partition or coincident with the module line thereof. The sum of the thicknesses of the insulation strip 42 and finish panel 43 is equal to the thickness of the similarly constructed panels 17' to provide a smooth unbroken wall surface. The construction of stud member 26 making it possible to combine a pair of them to provide stud structure 47 also adds to the flexibility of the arrangement of the building partitions in that one of the parts or studs of the stud structure 47 may be replaced by the stud structure 45, for example, to erect an additional wall (not shown) normal to wall 12 or the entire stud 47 may be replaced by two of the studs 45 to erect walls extending from and joining opposite sides of wall 12.

In Figures 8 and 9, there is shown another type of studding to provide a single panel joint. This studding comprises a pair of elongated metallic members 48 having abutting inturned side flanges 49 which are arranged to abut on the module line or medial plane of the partition. At top and bottom, the stud members 48 have upper and lower extended portions 50 apertured to receive screws for securing the stud to floor and ceiling securing strips 65 which are arranged in planular relationship with the partition 12. It will be seen that if the width of the panel is increased, a stud of the type of one of the studs of stud structure 48 may be used in place of one of the members of stud 47, thus providing different paneling arrangement on opposite sides of the partition 12 with single panel joints on one side and double panel joints on the other. Also if desired, the entire double stud of Figure 8 could be substituted for stud 47 to provide single joint paneling on both sides of the partition.

Where interior wall 12 joins another interior wall 13, which is parallel to interior wall 11, there is a stud structure 53 comprising the stud 55 and the stud 26 combined. Another type of studding, as at 54, is had by combining stud 24 and stud 25 for a corner formed by interior walls, such as the walls 13 and 14. In addition, where a wall terminates intermediate or spaced from other walls as does interior wall 14, or where the wall terminates at a doorway or arch, a terminating or end stud structure 55 is provided. This terminal stud structure 55 is similar to stud structure 47 in comprising a pair of metallic stud members 56 having inturned, side edge abutting flanges 57, arranged to abut in a vertical plane coincident with a selected module line. This stud structure 55, like the stud of Figures 8 and 9 is provided with upper and lower extended end portions 50 where the stud structure is secured to the upper and lower channels 65 preferably by self-threading screws. The stud structure is arranged to extend partly between the panels 17', the outer end portion of the stud structure being covered by a terminal section of U-shape cross section preferably formed by a pair of panels 59. These panels 59 may be of L-shaped cross section having laterally extended portions 60 forming an end wall with opposed abutting edges forming a joint along the end of the wall, the inner corresponding side edges of the panels abutting the opposed side edges of the panel 17'.

Counter-sunk screws, such as the screws 38 used to secure panels 17' in place, Figure 12, may be used to secure the terminal paneling 59 and the stud structure 55 together. In accordance with the modular plan, the widths of the terminal panels 59 are made equal to the thickness of the partition. It will now be seen that by using the three studs 24, 25 and 26 singly in certain locations and by combining them in various ways in other locations, as above pointed out, all of the studding requirements of a building are met.

The width of the panels 17 and 17' satisfy the formula $W=xM-T$. In this formula W is the width of the panel 17 or 17' and x is a whole number representing the number of modules between transverse module lines adjacent the opposite sides of the panel and passing through the studs at the opposite sides of the panel. The thickness of the partition is represented by T and M is the distance between adjacent module lines. For the panels of partition 12, $x=3$ and 1 and in the interior partition of the exterior walls, x for panels 17 equals 1, 2 and 3. These panels have a variety of widths but the width of each satisfies the formula, $xM-T$.

Referring now more particularly to Figure 15, showing a vertical sectional view of exterior wall paneling taken through stud 26, the upper and lower metallic straps or extensions 41, as in the case of stud 25, are provided with slots there-through which align with apertures in the finish panels 43 to receive screws 43' which screw into threaded apertures in the supporting strips 20 to secure the studs thereto. As previously mentioned, the slotted apertures in the straps 41 permit vertical adjustment of the metallic stud member 49 for properly aligning its screw holes with corresponding screw holes in the finish panels. The screw holes in the finish panels 43 are preferably countersunk so that the heads of screws 43' will be flush or a little below the surface of the panel and these screws are preferably covered by suitable upper and lower trim moldings 62 and 63 respectively. As shown in Figure 14, the studs of the interior walls or partitions are secured at their upper and lower ends to the channel-like anchor members 65 which in turn are secured respectively to the floor and ceiling by screws 66. These channel-like members 65 are arranged such that the vertical medial planes thereof coincide with selected module lines.

In paneling a room, the upper and lower stud supporting strips 20 and stud supporting channels 65 may first be secured to the floor and ceiling. The supporting strips 20 for the exterior walls 11 are positioned such that their vertically bent portions 22 seat against the inner surface of the exterior wall 11, thus coinciding with the module line or a vertical plane coincident therewith. Studs 24, 25 and 26 and 45 are then located in the desired places along the exterior wall 11 and in relation to the module lines extending perpendicular to the wall. For example, corner stud 24 may be erected and be secured at top and bottom thereof to the upper and lower securing strips 20 by the self-threading screws 30, Figure 16. When this stud 24 is secured in place, it will be seen, Figure 4, that its reversely bent flanges 29 seat respectively against the two wall surfaces at the corner of the room and that the outer surfaces of these reversely bent flanges 29 are coincident respectively with the intersecting module lines. Next, the double stud 45, formed by two of the corner studs 24 may be erected, it being understood that this type of stud will be used

wherever it is desired to erect an interior wall or partition, such as the wall 12. In erecting the stud 45, two corner studs 24 are arranged such that corresponding reversely bent seating flanges 29 thereof are in spaced relation, seating against the exterior wall inner surfaces 10 and such that the other corresponding reversely bent flanges engage each other in the vertical plane of or coincident with a module line extending vertically from the exterior wall. The two studs 24, like the corner stud, Figure 16, have upper and lower extended angle portions 27 where they are secured by self-threading screws 30 to the upper and lower exterior wall panel securing strips 20 and to the upper and lower partition securing strips 65.

The angle-like stud 25, carrying insulation and finish strip panels 34 and 35 respectively may be readily erected and secured in place as a unitary structure, the reversely bent flanges 32 thereof seating against the inner wall surfaces of the corner walls 11. This type of stud structure is constructed similarly to the stud structure of Figures 11 to 15 inclusive, the finish board 35 and metallic straps 33 extending beyond the upper and lower ends of stud member sides 31 and apertured to receive self-threading screws which screw into the upper and lower securing strips 20 to secure the stud thereto. In this form, the stud structure 25 comprises the angle metallic member 25', the insulation board 34, the metallic straps 33 and the finish panel 35 which are secured together and to the securing strips 20 by the stud securing screws 43'.

The provision of stud 26 adds to the flexibility of partition arrangement to the building. The finish board 43 extends respectively above and below the upper and lower ends of the metallic stud member 26 where it is apertured to receive screws for securing the stud structure to the upper and lower securing strips 20 for exterior wall paneling and to the securing strips 65 for partition paneling. These types of stud members 25, 26 and also stud structures 45, 47, 53 and 54, provide what may be termed double panel joints and stud 26 can be replaced by a stud, such as stud structure 45, if it is desired to erect a partition at this location. With the various exterior wall studs 24, 25, 26 and 45 secured in place, the panels 17 can now be readily erected and secured to the studs by screws 38 or 31', which screw-thread into the metallic members of the studs, Figures 10 or 16, to secure the panels thereto.

In the erection of interior walls or partitions, such as for example, the partition 13, a module line is selected, depending upon the desired size of the rooms, and the partition 13 is erected such that its vertical medial plane will coincide with the selected module line. Such partition 12 is to be erected, a three piece combination stud 53 is employed, comprising two of the stud members 24 together with one of the studs 26. The panels 17' may then be applied to complete wall 13 on opposite sides thereof, and the panels may be secured by screws to the studs.

By reason of the present modular plan of building erection and the particular construction and location of the studs, the length of the partition 12, i. e. the distance from the inner paneled surface of exterior wall 11 to the inner paneled surface of interior wall 13, will equal $X-M-T$. In this formula, M equals the distance between the module lines, X equals the number of modules between the module line at surface 10 and the module line forming the center line of partition

13 and T equals the thickness of the partition which is also equal to the widths of the stud panels which provide the double panel joints. Intermediate the exterior wall paneling and the parallel partition 13, one or more of the studs 47, depending upon the length of the partition, may be erected to provide additional support for the paneling. Where the panels 17' of rooms on opposite sides of the partition 12 are to be of the same width, two of the studs 26 may be combined to provide a double stud, designated generally by the numeral 47 which, of course, provides for double panel joints at the studs. The partition 12 is located such that its vertical medial plane coincides with a desired module line 15 and the stud 47 is located centrally thereof with respect to transverse planes coincident with module lines. As above mentioned, the widths of the insulation and finish board of the studs 26 are made equal to the width of the partition whereby the total of the widths of all of the panels 17' equal XM-TY where M is the distance between module lines, X equals the number of modules between module lines located within the partitions between which partition 12 runs, T is the thickness of the partition and Y the number of panels in the partition. As shown in Figure 4, the studs 26 are arranged with their corresponding 20 reverse bent flanges in relatively abutting relation, spacing the panels apart and providing seating surfaces for adjacent panels 17' which are secured thereto by screws.

At the corner formed by the partitions 13 and 14, the studding includes corner stud 25 and corner stud 24 arranged with their corresponding 35 reverse bent flanges in abutting relation to space the paneling of the two walls, as well as provide a rigid stud to which the panels may be secured. Partition 14, like parallel partition 12, is located such that its vertical medial plane coincides with a module line and the surfaces of the stud reverse bent flanges contact each other in a plane coincident with the module lines. Thus, the length of partition 13, if double joints 40 are used, equals XM-T and the width of each of the panels equal

$$\frac{XM - TY}{Y}$$

where Y equals the number of panels in the partition and X equals the number of modules between the module lines located within the partitions at the ends of partition 13 providing the panels are of equal width. The insulation and finish board of the stud member 25 extend above and below the metallic part of the stud where they are apertured to receive screws for securing the stud to the ceiling and floor securing members 65. The central angle portion of the stud 24 extends above and below the flanges thereof 55 to receive self-threading screws 30, as shown in Figure 16, for securing this part of the two-part stud to the stud securing members 65 located along the floor and ceiling.

The wall or partition 14 is shown terminating at what may be a doorway or arch and at this location, the stud 55 is erected. This stud 55 is provided with upper and lower extended end portions for securing the stud by screws to the ceiling and floor securing members 65 in a manner similar to that shown in Figure 14. Where a different paneling arrangement is desired on one side of a partition then on the other, the type of two-part stud shown in Figure 9 may be employed. For example, one of these studs 48 75

may be substituted for one of the stud members 26 of stud 47 with the result that double joint paneling at the stud would be had on one side of partition and single joint paneling on the other or double and single joint paneling can be had on the same side of the partition, as desired. This, of course, entails the use of two different width panels but provides for variation and flexibility of partition paneling.

Referring now to the modified form of building structure shown in Figures 17 to 24 inclusive, the numeral 70 designates generally an exterior wall of a building and the numerals 71 and 72 respectively designate generally the floor and ceiling, respectively, of a room of the building, see Figure 20. Secured to the floor 71 by nails, screws or any other suitable means is a plurality of end to end aligned retainer channels 73 which are disposed against the inner surface of the exterior wall 70 with their side reinforcing flanges extending upwardly. Similar, channel retainer members are secured to the ceiling 72 against the inner surface of the exterior wall 70 with the channel flanges extending downwardly in vertical aligned relation to the upwardly extending channel flanges on the floor 71.

This building structure, like the previously described structure, is laid out on a modular plan represented in Figure 17 of the drawings by the horizontally extending, equally spaced parallel lines 76 intersecting the perpendicular and equally spaced parallel lines 77 dividing the area within the exterior walls 70 into a predetermined number of equal squares, the squares being herein referred to as modules and the intersecting lines as module lines. Also, as in the previously described building, the inner wall surfaces of exterior walls 70 coincide with a selected horizontal module line and the outer flanges of the upper and lower retainer channels are also coincident with the same horizontal module line.

Stud or fastener members 78 have upper and lower end portions respectively held in the upper and lower retainer channels 73, 75, the stud fastener members 78 preferably being metallic, elongated channel-like members to extend from the bottom wall of the lower retainer channels 73 upwardly into the upper retainer channels 75. As shown in Figure 24, the studs or fastener members 78 each comprise a vertical, flat wall portion 79 from which extend converging sides 80 having oppositely directed outturned flanges 81 reversely bent with edge portions 82 thereof extending in converging relation into the channel-like fastener member. The inturned converging flange portions 82 are provided to receive therebetween the side flanges 83 a pair of angle clip members 84 which are in part frictionally held in place by the tensioned force of the flange portions 82. Each of the finish panels, designated by the numeral 85, is provided with a pair of clip members 84, located and extending along each side of a panel adjacent the longitudinal edges thereof, and located on the same and inner side of the panel. A flange 86 of the angle members 84 may be secured, such as by screws, to a finish panel 85 and arranged such that the other flange 83 of the angle member extends perpendicular to the panel surface with the outer surface of flange 83 preferably flush with the side edge of the panel. Each of the flanges 83 is preferably indented at spaced intervals along its length to provide a plurality of slightly extended surface portions 88 which are located so as to catch behind the edges of the

11

converging fastener sides 82 to hold the panels in place. It will be seen that the flanges 83 of adjacent panels and the panel edges fall on or are coincident with a module line, extending transversely or perpendicular to the exterior wall 70.

The area within the exterior walls 70 may be divided into a number of rooms 90, 91 by interior walls or paneled partitions designated generally by the numerals 92, 93 and 94, see Figure 17. As is more clearly shown in Figures 21 and 22, the interior walls 92, 93 and 94 each include a pair of stud retainer channels 95, 96 seating on and secured to the floor 11 with the channel flanges extending upwardly. These channels 95, 96 15 preferably extend the width or length of the room, as the case may be, with adjacent opposed side surfaces of the channels in abutting relation with each other and arranged in accordance with the modular plan such that the contacting flange surfaces of the channels are coincident with module line, as seen in Figure 17. In other words, the interior walls 92, 93 and 94 are erected such that the vertical medial planes thereof respectively coincide with the module lines chosen for the locations of the interior walls or partitions. Likewise located, with respect to the chosen module lines is a pair of parallel channel members 97, 98 secured to the ceiling 72, Figures 20, 21, with the relatively parallel flanges extending downwardly. These upper channels 97, 98, the lower channels 95, 96, and the upper and lower retainers 73, 75 of the exterior wall paneling are all alike so as to reduce manufacturing cost and facilitate shipping and assembly of the structural parts of the building. The studs or fasteners 78 are retained at their upper and lower ends in the upper and lower retainer channels but may be shifted along in the channels for adjustment purposes. These fasteners 78 and the cooperating fastener members 84 are the same in form and construction as the fasteners previously described in connection with the paneling of the exterior walls 70.

At the corners of the rooms, see Figure 17, preferably rounded finish panels 99 are provided and arranged such that the room wall corner surface is convexly curved and each finish panel is preferably provided with an outer metallic reinforcing panel 103 having its side edges terminating at the studs. Where the interior wall 92 joins the paneling of exterior wall 70 and the paneling of interior wall 93, panel studs or fasteners 78, 84 connecting the rounded corner panels 99 to the adjacent panels of wall 92 are oppositely disposed or aligned in the same plane, as seen in Figure 17. However, the intermediate studs or fasteners 78, as shown in Figures 17 and 19, may be arranged, if desired, in staggered relation to each other to provide for different paneling arrangement on opposite sides of the partition. This requires the use of panels of different width in the construction of the partition or wall 92.

In the interior wall 93, a door 102 may be provided having metallic, frame or trim members 103, 104 secured to adjacent panels by means of the studs and clip members 78, 84. These side frame members 103, 104 are preferably constructed of sheet steel having a front finish wall or trim facing 105 and a spaced rear wall or facing 106 having inturned spaced flanges 107. The rear facing wall 106 of the frame member 103 seats against the end edges of the rounded corner panels 99 at the exterior wall, whereas the rear 75

12

wall facing 106 of the frame member 104 seats against the end edges of one of the partition panels 95, and against the edge of the partition rounded panel 99. Panel fastening clips 84 carried by and secured respectively to the rounded corner panels 99 and to the inturned flanges 107 of the frame members snap into the studs or fastener 78 to secure the corner panels 99 and door frame member 103 together. Similarly, clips 84 carried by and secured to inturned flanges 107 of the door frame member 104 and by the adjacent side edges of the partition panel 95 snap into the oppositely disposed studs or fasteners 78 to secure the door frame members 104 to the partition 93.

In Figure 18, there is shown a construction in which a door 110 is located in a partition on each side of and adjacent to a joining partition, designated generally by the numeral 111. In this instance, a pair of door frame members 112 have rear facing walls 113 seating respectively against the end edges of the rounded corner panels of the partition 111 and also seat respectively against opposite edges of a wall finish panel 115. Studs or fastener members 78 have their upper and lower ends held in retainer channels 95, 96 at the floor and ceiling respectively. The rounded corner panels 99, door frame members 112 and finish panel 115 carry clips 84 cooperable with the fasteners 78 to secure the parts of the structure together.

Referring now to the partition 94, this partition terminates, such as at an archway, in a rounded end wall section, designated generally by the numeral 116, see Figure 17. The terminal partition section 116 is of general U-shape in cross section including an outer finish panel 117 having its side edges abutting respectively the side edges of adjacent panels 95. Secured to the finish panel 117 is an inner metallic reinforcing liner 118 of general U-shape having a reversely bent central portion 120 providing an end wall 121 transversely to the partition 94. Welded or otherwise secured to this transverse wall 121 is a pair of the panel fastener clips 84 cooperating with a stud or fastener 78 disposed within the U-shaped partition section 116. The terminal stud 78 may have its wall 79 welded or otherwise secured at top and bottom to the ends of the floor and ceiling channels 95, 96.

In the above described modification, the distance from the exterior wall 70 module line to the inner surface of the exterior wall panels is equal to one-half the thickness of the interior walls or partitions 92, 93 and 94. Also, the distance from the inner surface of the exterior wall panels to those edges of the rounded corner panels 99 which are parallel to the exterior wall module line is equal to one-half the thickness of the interior walls. Consequently, the overall length of the partitions of this single joint paneling system can be expressed by the formula $XM-T$ previously mentioned in connection with double joint paneling of the construction of Figures 1 to 16 inclusive. Thus, the two forms of the invention have in common, among other things, that the length of the partition is equal to $XM-T$, where X is any whole number which expresses the number of modules between module lines located within the partitions between which the partition in question extends, M is the distance between module lines and T is the thickness of the partition.

I claim:

In a building construction having a pair of ex-

13

terior walls joining at a corner, the exterior walls each having an inner wall surface, one stepped stud member at the corner, an interior panel for each of the exterior walls and seating on said one stud member, the said one stud member having seating surfaces coplanar with and engaging the respective inner wall surfaces and having stepped seating surfaces positioning the inner surfaces of the interior panels a predetermined distance from the respective inner wall surfaces of the exterior walls and spacing each of the adjacent lateral edges of the interior panels from the opposite inner wall surface a distance equal to said predetermined distance, a partition extending in a direction normal to one of the exterior walls, the partition including oppositely spaced apart panels extending inwardly from said one exterior wall, a pair of stepped stud members similar to the one stud member arranged back to back each with a seating surface coplanar with and engaging the inner wall surface of said one exterior wall, adjacent interior panels for said one exterior wall seating on stepped seating surfaces of the pair of stud members, the last mentioned interior panels being positioned with their inner surfaces spaced inwardly from the inner surface said predetermined distance and with their opposed edges spaced apart a distance equal to twice said predetermined distance, and the oppositely spaced apart partition panels seating on the pair of stud members, the pair of stud
